United States Patent Office

Des. 185,387
Patented June 2, 1959

185,387

ADDING MACHINE CASING

Carl L. Otto, New York, N.Y., assignor to Underwood Corporation, New York, N.Y., a corporation of Delaware

Application April 14, 1958, Serial No. 50,471

Term of patent 14 years

(Cl. D64—11)

FIG.3

FIG.4

Figure 1 is a front perspective view of an adding machine casing showing my new design;

Figure 2 is a rear perspective view thereof;

Figure 3 is a side elevational view of the adding machine casing shown in Figure 1; and

Figure 4 is a front elevational view thereof.

I claim:

The ornamental design for an adding machine casing, as shown.
